DUPLEX ELECTROMAGNETIC VIBRATORY UNIT

Filed May 24, 1926

Inventor
W. HEUSSER,

By *A. Mellinckrodt*
Attorney

UNITED STATES PATENT OFFICE.

WILFRID HEUSSER, OF SALT LAKE CITY, UTAH.

DUPLEX ELECTROMAGNETIC VIBRATORY UNIT.

Application filed May 24, 1926. Serial No. 111,456.

This invention relates to a duplex electromagnetic vibratory unit especially for use as a loud speaker, and its principal objects are to provide an instrument which shall:

5 First. Be faithfully responsive to the most delicate tones and tone variations.

Second. Be equally as responsive to the heavy tones with extreme variations.

Third. Be sturdy in construction and 10 therefore free from operating troubles.

Fourth. Keep the vibratory member or members free from a super-imposed tensioning.

Fifth. Be compact, and simple to manu- 15 facture.

These objects are attained to an eminent degree by (a) distributing the magnetic flux, operative on an armature, over substantially the entire main superficial area thereof, in- 20 stead of concentrating the flux on only fractional parts of this area; (b) constructing the spool of the electromagnet in a novel manner to obtain strength, and to accommodate the pole pieces and magnetic conductors 25 by which the unique distribution of the flux is accomplished; (c) magnetizing the pole pieces by induction simultaneously with the armature, in addition to the magnetization thereof by the usual permanent magnet; (d) 30 mounting the diaphragm so that the pressure of the confining members shall be uniform under all temperature conditions.

The armature and mounting constituting the subject of a separate application for 35 U. S. patent filed by me September 24, 1926, Serial No. 111,455, is designed to be used in conjunction with the present invention, for obtaining the best results.

The features of this invention for which 40 the protection of Letters Patent is desired, are collectively grouped in the claims which conclude this specification.

In the drawing, illustrating merely one embodiment of this invention:

45 Fig. 1 represents a top plan;

Fig. 2, an elevation in the direction of the arrow 2, Fig. 1;

Fig. 3, a section on line 3, Fig. 1;

Fig. 4, a fragmentary section on line 4,

50 Fig. 1;

Figs. 5 to 8, details of the spool structure and pole pieces only, Fig. 5 being a section on line 5, Fig. 7;

Fig. 6, a section on line 6, Fig. 5;
Fig. 7, an elevation in the direction of arrow 7, Fig. 5;

Fig. 8, a section on line 8, Fig. 5, part broken away.

Referring to the drawing, 40 indicates a base having the ferrule 41 for connecting to the usual horn or other amplifying device (not shown).

Mounted on the base is a cap 44 which latter is recessed to receive the diaphragm 45 as well as the raised annular portion 46 of the base which bears against the circumferential margin of the diaphragm. Screws 47 have the body 48 shouldered to bear against the lower face of cap 44 and are drawn tightly against the face of the cap by means of the threaded end 49. Springs 50 exert uniform pressure upon the marginal bearing area of the diaphragm, thereby eliminating evils resulting from gripping the diaphragm too tightly, or having it too loose, especially from changes in temperature.

On the cap 44 are mounted U-shaped permanent magnets 31 having their poles 31¹ of the same polarity opposed to, and slightly spaced apart from, each other. These magnets are clamped down tightly by means of the U-bolts 52, whose legs 53 pass through holes in the cap 44 and secured by the nuts 54, the latter being disposed in blind recesses in the under side of the cap. Lugs 42 having holes 43 may be provided for fastening the cap to any suitable supporting structure such as a cabinet.

Held between the legs of the magnets 31 at their polar extremities and clamped in place by bolts 52, is the spool 55, which has a number of new features, and forms an important part of the electromagnet. The spool 55 is made up of the body sleeve 10 (Figs. 5 to 8) and the body flanges 12 which parts may be made of non-magnetic material such as brass, and be united to each other by soldering their contacting surfaces to each other as at 56. Pole pieces 57, preferably made of silicon steel, extend through the sleeve from end to end, substantially parallel to the surfaces of the armature (Figs. 2 and 3) in its neutral position. Each pole piece may be united to the corresponding inner surface of the sleeve by soldering, as at 58.

In intimate contact with the pole pieces 57, are the magnetic conductors 14 and 14¹, which may be made of iron and held rigidly in place by soldering as at 60, to the flanges 5 12 of the spool. Pins 17 are rigidly fastened in the pole pieces and sleeve, and have the notched faces 19 for receiving the armature. The armature is held in place by means of the spring rigging, consisting of 10 the tie 26, the yoke 27, and the spring bar 28 having cradles 30 integral with the legs 30¹ which are mounted in the spool 55 as indicated in Figs. 1, 2 and 3, and as described in detail in my other application for patent, 15 previously mentioned herein.

A gap 61 may be cut through the flanges and sleeve of the spool, bifurcating it to admit the tie 26 and to prevent the formation of transformer currents in the spool 20 structure due to the action of the electromagnet coil.

The position of the armature within the spool is indicated by dotted lines in Fig. 6, which, together with the showing in Figs. 25 2 and 3, makes clear the fact that the main superficial area of the armature is substantially equal to, and superposed in registry with, the main superficial areas of the pole pieces, so that the magnetic flux in bridging 30 the gap from one set of pole pieces to the other set, virtually permeates the armature at every point thereof.

In operation, the magnetic flux from one 35 pair of similar poles of both permanent magnets, follows the conductors to and through the corresponding pole piece, and is applied over substantially the entire superposed and registering area of the armature, as just described, reaching the opposite pair of similar poles through the armature, through the 40 opposite pole piece and through the opposite conductor, thus completing the magnetic circuit. This arrangement makes extremely favorable use of the magnetic energy.

The coil 62 of the electromagnet is wound upon the spool 55 and the electromagnet action is such that the pole pieces and the armature are inductively influenced simultaneously, with the result that slight variations 50 in the electric current exercise a relatively large unbalancing effect on the armature and hence on the diaphragm also.

Using two permanent magnets arranged 55 as clearly shown in Fig. 2, produces an independent magnetic circuit in each half of the said unit and results in a particularly strong and advantageous magnetic action upon the armature, whose motion is transmitted to the diaphragm through tie 70.

While a specific embodiment of this invention is herein shown and described, it is to be clearly understood that the detailed parts thereof, may, or may not, be shown in the 65 preferred forms, and further, that the pre-

ferred forms may be varied from time to time, as the development of this invention and the arts with which it is identified, progress. Therefore, that which forms an essential and characteristic part of this invention will be readily discernible from the claims in which its spirit is generalized.

Having fully described my invention what I claim is:

1. An electromagnetic vibratory unit, comprising an oscillating armature, pole pieces having their principal superficial areas lying in planes on opposite sides of, and substantially parallel to, the plane of said armature in its neutral position, a source of magnetism, an armature operatively positioned between the said pole pieces, and an electromagnet arranged to inductively influence said armature.

2. An electromagnetic vibratory unit comprising a permanent magnet, pole pieces substantially parallel to each other, an armature operatively positioned between the pole pieces, an electro-magnetic coil arranged to influence said armature and pole pieces simultaneously, and magnetic conductors extending from the poles of said permanent magnet to the said pole pieces.

3. An electromagnetic vibratory unit comprising an electro-magnetic coil having an aperture therethrough, an armature operatively positioned within said aperture, pole pieces spaced apart from and paralleling said armature on either side thereof, and a source of magnetism arranged to maintain a magnetic flux in said pole pieces.

4. An electromagnetic vibratory unit comprising an electro-magnetic coil having an aperture substantially through the center of winding thereof, an armature mounted to oscillate within said aperture, pole pieces substantially paralleling the said armature in its neutral position, and means for establishing a magnetic flux in said pole pieces.

5. An electromagnetic vibratory unit comprising a coil having a sleeve, pole pieces spaced apart from and paralleling each other within said sleeve, forming integral parts thereof; flanges at both extremities of said sleeve, magnetic conductors closely contacting said pole pieces and forming integral parts of said flanges, and U-shaped permanent magnets having their poles contacting the said conductors.

6. An electromagnetic vibratory unit comprising U-shape permanent magnets, a spool held between the legs thereof, said spool having a non-magnetic sleeve, pole pieces lying wholly in planes paralleling said sleeve, magnetic conductors extending from said magnets to said pole pieces, a supporting structure for said magnets, and means holding said magnets upon said structure.

7. An electromagnetic vibratory unit comprising an armature, pole pieces spaced apart

from, and paralleling said armature, on either side thereof, said pole pieces substantially overlying the major superficial face of the armature, and an induction coil for simultaneously magnetizing said armature and said pole pieces.

8. An electromagnetic vibratory unit comprising an armature, pole pieces spaced apart from, and paralleling said armature, on either side thereof, a permanent source of magnetism arranged to influence said armature, and a source of electromagnetism arranged to simultaneously influence the said armature and the said pole pieces.

15 9. An electromagnetic vibratory unit comprising a base, a cap mounted thereon, an armature having a marginal bearing between said cap and base, means for maintaining a uniform pressure upon said bearing, permanent magnets mounted on said cap, an electro-magnetic coil held by said permanent magnets, an armature within the said coil pole pieces, paralleling said armature so armature and pole pieces will be simultaneously influenced by said coil, conductors from said magnets to said pole pieces, and a connection from said armature to said diaphragm.

30 10. A spool comprising a sleeve, flanges at either end of said sleeve, upper and lower pole pieces substantially identical with the upper and lower portions of said sleeve, and magnetic conductors substantially identical with said flanges, said conductors being in close contact with said pole pieces.

35 11. A spool comprising a sleeve, flanges at either end of said sleeve, upper and lower pole pieces substantially identical with the upper and lower portions of said sleeve, and magnetic conductors substantially identical with said flanges, said sleeve, flanges, pole pieces and magnetic conductors being bifurcated.

40 12. A spool structure having a sleeve, upper and lower pole pieces substantially integral with said sleeve, said sleeve being made of non-magnetic material, means for mounting an oscillating armature within said sleeve, and means for holding an electromagnetic coil on said sleeve.

45 13. A spool comprising a non-magnetic sleeve, non-magnetic flanges fastened to opposite ends of the sleeve, pole pieces fastened opposite each other within said sleeve, and magnetic conductors extending from said pole pieces outwardly along said flanges.

50 14. A spool comprising a non-magnetic sleeve, non-magnetic flanges fastened to the sleeve at opposite ends thereof, pole pieces fastened within said sleeve in opposite relation to each other, and magnetic conductors in magnetic contact with said pole pieces, as

said magnetic conductors being contiguous to said flanges.

55 15. A spool comprising a non-magnetic sleeve having two opposite plane portions, non-magnetic flanges fastened to the sleeve at opposite ends thereof, plane pole pieces fastened to the plane portions of said sleeve along contiguous surfaces thereof, and magnetic conductors extending from said pole pieces outwardly along said flanges.

60 16. A spool comprising a non-magnetic sleeve having two opposite substantially plane surfaces defined therein, non-magnetic flanges fastened to the sleeve at opposite ends thereof, substantially plane pole pieces soldered to the plane surfaces of said sleeve, and substantially plane magnetic conductors soldered to the said flanges along contiguous surfaces thereof.

65 17. A spool comprising a non-magnetic sleeve, non-magnetic flanges fastened to opposite ends of the sleeve, pole pieces fastened opposite each other within said sleeve, and magnetic conductors extending from said pole pieces outwardly along said flanges, said spool being bifurcated to define a gap extending through said sleeve, pole pieces, flanges and conductors.

70 18. A spool comprising a non-magnetic sleeve, non-magnetic flanges fastened to the sleeve at opposite ends thereof, pole pieces fastened within said sleeve in opposite relation to each other, and magnetic conductors in magnetic contact with said sole pieces, as well as contiguous to said flanges; said sleeves, flanges, pole pieces and conductors having a co-extending gap defined therein.

75 19. A spool comprising a non-magnetic sleeve having two opposite plane portions, non-magnetic flanges fastened to the sleeve at opposite ends thereof, plane pole pieces fastened to the plane portions of said sleeve along contiguous surfaces thereof, magnetic conductors extending from said pole pieces outwardly along said flanges; and a gap defined across said spool, said gap extending through said sleeve, pole pieces, flanges and conductors.

80 110 20. A spool comprising a non-magnetic sleeve having two opposite substantially plane surfaces defined therein, non-magnetic flanges fastened to the sleeve at opposite ends thereof, substantially plane pole pieces soldered to the plane surfaces of said sleeve, substantially plane magnetic conductors soldered to the said flanges along contiguous surfaces thereof; and a gap defined across said spool.

115 120 In testimony whereof, I sign my name hereto.

WILFRID HEUSSER.
